UNITED STATES PATENT OFFICE.

ELLSWORTH A. HAWTHORNE, OF BRIDGEPORT, CONNECTICUT.

ILLUMINATING APPARATUS.

1,314,589.

Specification of Letters Patent.

Patented Sept. 2, 1919.

Application filed July 13, 1916. Serial No. 109,022.

To all whom it may concern:

Be it known that I, ELLSWORTH A. HAWTHORNE, a citizen of the United States, and a resident of Bridgeport, county of Fairfield, and State of Connecticut, have invented an Improvement in Illuminating Apparatus, of which the following description, in connection with the accompanying drawings, is a specification, like characters on the 10 drawings representing like parts.

This invention relates to an illuminating apparatus, and is more especially concerned with an apparatus particularly intended and adapted to be carried by a vehicle, and 15 capable of efficiently illuminating the roadway, yet without causing a blinding glare which would interfere with the vision of persons facing the illuminating apparatus.

My invention will be best understood by 20 reference to the following description, when taken in connection with the accompanying drawings showing one illustrative embodiment thereof, while its scope will be more particularly pointed out in the appended 25 claims.

In the drawings:

Figure 1 is a front elevation of an illuminating apparatus embodying my invention; and

30 Fig. 2 is a sectional view on line 2—2 of Fig. 1.

Referring to the drawings, and to the embodiment of my invention which I have selected for illustration, I have there shown 35 a lamp of the general type employed as a head-light for motor vehicles, although the invention is by no means restricted to such use. The lamp shown comprises a usual casing 1, in which is mounted a suitable 40 source of light 2, herein an incandescent electric bulb with which is associated a usual beam reflector 3, herein of the parabolic type, that is, a paraboloid or surface of revolution formed by revolution of a paraboloid about its axis—in coaxial relation 45 with the lamp bulb. The lamp casing may be provided at its front with a suitable light-transmitting element 4, similar in most respects to the usual front lens or glass, to 50 transmit the light in a forward direction, while excluding dust and moisture from the interior of the lamp casing.

In the use of lamps of this general class, some of the objectionable glare which blinds 55 and confuses persons facing the light is due to the direct rays of light from the light

source, while another part of the glare is usually caused by a portion of the surface of the parabolic reflector, depending, of course, upon the height at which the lamp 60 is placed with relation to the ground, and hence bearing a direct relation to the level of the eyes of a person facing the lamp.

As a means for cutting off the direct rays of light in the direction of the axis of the lamp and reflector, I may employ a suitable screen, herein comprising a tube 5 arranged co-axially with the lamp bulb and reflector, and having a diameter approximately equal to that of the lamp bulb. This tube may be 70 conveniently supported by the front glass 4, the latter for that purpose being provided with an inwardly projecting hub or boss 6, encircled by the forward end of the tube, the rear end of the latter extending 75 to a point closely adjacent the lamp bulb. This tube may be, and preferably is, opaque, and the inner surface of the boss 6 which it encircles may be frosted, or rendered opaque by covering the same with some suitable opaque substance such as a coating 7 of paint or enamel, thereby constituting a screen which effectually cuts off the direct rays of light in the direction of the beam projected by the reflector. The tube may 80 be secured to the boss by fitting it tightly thereto, and in addition may be cemented if desired. Since the screen will cut off the diverging rays of light emitted directly from the bulb 2, the only light sent forth 85 by the lamp will be the parallel rays from the reflector 3. As light is transmitted in straight lines the light will therefore be sensible only from a position in front of the light and the direction of observation 90 of the light source is thus limited.

As a means for eliminating the objectionable glare from the reflector, the portion of the latter which causes the glare may be screened or cut off from the source of light 100 by suitable means, herein a screen 8. The latter may be of any appropriate size and shape to meet the requirements of the situation, but herein, as indicated in Fig. 1, has the form of a sector; in other words, it has 105 two edges 9—9, which are generally radial with reference to the axis A—A of the lamp and reflector, and a third edge 10, which is in a plane B—B substantially at right angles to said axis.

The shield 8 may be supported, preferably 110 in close proximity to the internal surface of

the reflector 3 by any suitable means, herein a support 11 in the form of an arm, or a pair of arms, formed by bending a suitable strip of material to form a collar 12 encircling the tube 5, and a pair of arms 13-13, whose terminal portions 14-14 are secured to the shield 8 by appropriate means, herein rivets 15-15. Any suitable means may be employed to enable the shield 8 to be adjusted axially or angularly with respect to the axis A-A, but herein for this purpose the collar 12 is provided with clamping means comprising a bolt 16 passing through the arms 13 and provided with a nut 17 by means of which the collar may be contracted and clamped onto the tube 5. By simply loosening this bolt, the desired adjustment may be effected, and the bolt again tightened.

20 It must now be apparent that the shield 8 provides a convenient means for limiting the effective area of the reflector, and by means of the adjustment, the non-effective area may be shifted or changed to suit the 25 particular conditions. For example, where the lamp is placed rather low upon the vehicle, it will usually be desirable to shield the lower portion of the reflector, and, on the other hand, when the lamp is placed at a 30 considerable height from the ground, it may be desirable to shield the upper portion of the reflector, the change of position of the shield being readily accomplished by simply loosening the adjustable support, then turning the shield to the proper position, and finally tightening the support in the selected 35 position of adjustment. In this connection, it will be observed that the glare preventing devices are mounted independently of the 40 lamp bulb 2, and may be removed as a unit with the front glass and its frame or bezel, without in any way disturbing the lamp bulb.

While I have herein shown and described 45 one form or embodiment of my invention for illustrative purposes, and have disclosed and discussed in detail the construction and arrangement incidental to one specific application thereof, it is to be understood that 50 the invention is limited neither to the mere details or relative arrangement of parts, nor to its specific embodiment herein shown, but that extensive deviations from the illustrated form or embodiment of the invention 55 may be made, without departing from the principles thereof.

Having thus described my invention, what

I claim and desire by Letters Patent to secure is:

1. An illuminating apparatus comprising, 60 in combination, a source of light, a beam reflector associated therewith, a glazing covering the front of the reflector, means mounted on said glazing in front of said source for limiting the direction of observation of said source, and means for limiting the effective area of said reflector, the last-mentioned means being supported by the first-mentioned means.

2. An illuminating apparatus comprising, 70 in combination, a source of light, a beam reflector associated therewith, means arranged coaxially with said source and reflector for limiting the direction of observation of said source, means for limiting the effective area 75 of said reflector, and means to support the second-mentioned means upon the first-mentioned means and to adjust the second about the axis of the first.

3. An illuminating apparatus comprising, 80 in combination, a source of light, a beam reflector associated therewith, means arranged coaxially with said source and reflector for limiting the direction of observation of said source, means for limiting the effective area 85 of said reflector, and an arm to support the second-mentioned means upon the first-mentioned means.

4. An illuminating apparatus comprising, 90 in combination, a source of light, a beam reflector associated therewith, means arranged coaxially with said source and reflector for limiting the direction of observation of said source, means for limiting the effective area 95 of said reflector, an arm to support the second-mentioned means upon the first-mentioned means, and means adjustably to secure said arm to the first-mentioned means.

5. An illuminating apparatus comprising, 100 in combination, a source of light, a beam reflector associated therewith, means arranged coaxially with said source and reflector for limiting the direction of observation of said source, means for limiting the effective area 105 of said reflector, a support comprising a strip of material bent to form a collar encircling the first-mentioned means, and a pair of arms whose terminal portions are secured to the second-mentioned means, and means adjustably to secure said collar to the 110 first-mentioned means.

In testimony whereof, I have signed my name to this specification.

ELLSWORTH A. HAWTHORNE.
